CLAIM

The ornamental design for a bottle, as shown and described.

DESCRIPTION

FIG. 1 is a side elevational view of a bottle showing my new design;

FIG. 2 is side elevational view thereof wherein the bottle has been rotated 90° with respect FIG. 1 and wherein a portion is broken away to more clearly illustrate the bottom;

FIG. 3 is a top plan view; and

FIG. 4 is a bottom plan view thereof.

The two sides of the bottle not shown are mirror images of the respective sides shown in FIGS. 1 and 2.

FIG. 1

FIG. 3

FIG. 2

FIG. 4
